C. V. LUCIUS.
METALLIC CASKET.
APPLICATION FILED MAR. 13, 1919.

1,326,873.

Patented Dec. 30, 1919.

UNITED STATES PATENT OFFICE.

CHRISTIAN V. LUCIUS, OF MASSILLON, OHIO.

METALLIC CASKET.

1,326,873.

Specification of Letters Patent. Patented Dec. 30, 1919.

Application filed March 13, 1919. Serial No. 282,410.

To all whom it may concern:

Be it known that I, CHRISTIAN V. LUCIUS, a citizen of the United States, residing at Massillon, in the county of Stark and State 5 of Ohio, have invented certain new and useful Improvements in Metallic Caskets, of which the following is a specification.

My invention relates to improvements in metallic caskets, and more particularly to 10 that class or type known as "combined burial caskets and grave vaults," which dispenses with the ordinary outer or "rough box" commonly employed with the ordinary burial casket.

15 The primary object of the invention is to provide a generally improved metallic casket of this class which will be exceedingly simple in construction, cheap of manufacture, and efficient in use.

20 A further object of the invention is the provision of a casket of this class made entirely of sheet metal and having its parts particularly arranged and disposed relative to each other so as to present welding edges 25 particularly adapted for "autogenous welding," as well as one which will be of attractive outline and ornamental appearance.

25 A still further object is the provision of a metallic casket of this class which will not 30 only be of great durability, as well as fluid proof, but also one which may be hermetically sealed through the medium of an improved cover supporting and sealing member and fastening and clamping members 35 connecting the latter with the casket cover.

35 A still further object is the provision of improved slide cover supporting members within the upper marginal edges of the casket body, together with non-metallic tack- 40 ing strips or members adapted to support the casket lining material or upholstering, as well as one which will present the appearance of an ordinary oak casket when the metallic casket cover is removed for the pur- 45 pose of viewing the remains.

With the above mentioned and other ends in view the invention consists in the novel construction, arrangement, and combination of parts, hereinafter described, illustrated in 50 one of its embodiments in the accompanying drawings, and particularly pointed out in the appended claims.

Referring to the drawings, forming a part of this specification, Figure 1, is a side elevation of a metallic casket constructed in accordance with this invention. 55

Fig. 2, an end elevation of the same.

Fig. 3, a cross sectional view taken on line 3—3 of Fig. 1.

Fig. 4, a view, partly in top plan and 60 partly in horizontal section, taken on line 4—4 of Fig. 1.

Similar numerals of reference designate 65 like parts throughout all the figures of the drawings.

The improved casket body is preferably made up of a single blank of sheet metal bent longitudinally of its length into substantially U-shape in cross section forming bottom and side walls 1 and 1^a, respectively, 70 as shown most clearly in Fig. 3 of the drawings. The end walls 1^b are preferably formed of a single blank of sheet metal having the sides thereof bent inwardly forming welding flanges 1^c, as shown most clearly in 75 Fig. 4 of the drawings.

The metallic casket body is provided about its upper and lower marginal edges with longitudinally extending metallic moldings 2 and 3, respectively, said upper and lower 80 moldings 2 and 3 being preferably of hollow formation and bent into any suitable and convenient form and attractive appearance.

The upper and lower moldings 2 and 3 85 are of rectangular shape and the upper molding 2 has its upper edge spaced from the upper marginal edges of the side and end walls 1^a and 1^b to receive an interposed casket cover supporting and sealing member 90 4 also of rectangular shape, said rectangular supporting and sealing member 4 being welded at 4^a about the upper marginal edges of the casket body and being seated within and welded to an upwardly extending flange 95 2^a of the upper metallic molding 2, as shown most clearly in Fig. 3 of the drawings.

As a further means of reinforcing and ornamenting the casket body the upper and lower moldings 2 and 3 are provided with 100 openings 2^b and 3^a, respectively, at the corner and intermediate portions thereof to receive and carry the ends of vertically extending corner and intermediate metallic moldings

5 and 6, respectively, said moldings being also of hollow formation and welded at their ends to the horizontally extending moldings 2 and 3, and at their sides to the side and 5 end walls 1^a and 1^b, respectively.

The casket cover 7 is preferably of concavo-convex shape in cross section, as shown, and is provided about its marginal edges with a horizontally extending marginal 10 flange 7^a adapted to rest above and to register with the covering supporting and sealing member 4, and as a means of hermetically sealing the cover to the casket body, the supporting and sealing member 4 is preferably 15 provided with a gasket 4^b, and as a means of securing and clamping the cover upon the gasket 4^b, the supporting and sealing member 4 is provided with a plurality of threaded openings 4^c adapted to removably receive 20 and contain a plurality of threaded fastening members, in the present instance, in the form of threaded bolts 8 terminating in wing heads 8^a by means of which the fastening members or bolts 8 may be drawn up. 25 When the cover 7 is removed the fastening members 8 are also removed, as shown in the central portion of Fig. 4 of the drawings, so that the casket will present the ordinary appearance of a casket, proper, when the remains 30 are placed therein and are reviewed by the relatives and friends of the deceased.

As a means of removably receiving and supporting suitable slide covers 9 and 9^a, the inner upper marginal edge of the metallic casket body is provided with slide supporting members 10 provided with horizontally extending spaced strips 10^a forming intervening guide or slide ways adapted to receive the marginal edges of the slide covers 35 9 and 9^a, the upper strips being removed by means of fastening members or screws 10^b, the removal of the upper strip 10^a permitting of the removal of the slide covers 9 and 9^a, the slide cover 9 at the head of the casket 40 being preferably of glass or other transparent material, while the cover 9^a is preferably of non-transparent or opaque material.

The slide supporting members 10 are preferably of non-metallic material, such as 50 wood or the like, and the slide supporting members 10, in the present instance, extends beneath the slide covers forming tacking strips 10^c to receive the nails or fastening members for connecting and supporting the upper edges of the casket lining material 11.

The sides and ends of the casket body may be provided with suitable casket handles 12 of any suitable and convenient form. It will be seen that the edges of the metal parts 60 and ornamental fittings are particularly well arranged for autogenous and other modern welding methods and processes, the casket, as a whole, presenting an ornamental appearance, and the exterior metal parts being 65 well adapted to receive a wood finish so that

the casket will present the appearance of an ordinary wooden casket.

From the foregoing description, taken in connection with the accompanying drawings, the operation and advantages of my 70 invention will be readily understood.

Having thus described one of the embodiments of my invention, what I claim and desire to secure by Letters Patent, is,—

1. A casket, comprising a metallic casket 75 body provided about its upper and lower marginal edges with metallic moldings, vertical corner and intermediate metallic column members extending therebetween, a casket cover supporting and sealing member 80 carried by said upper marginal metallic molding, a casket cover provided with a marginal clamping and sealing flange seated on said cover supporting and sealing member, a slide cover supporting member within 85 the upper marginal edges of said casket body, and slide covers in said slide cover supporting member beneath said casket cover supporting and sealing member.

2. A casket, comprising a metallic casket 90 body provided about its upper and lower marginal edges with hollow metallic moldings, vertical hollow metallic column members extending therebetween and welded thereto, a casket cover supporting and sealing member carried by and welded to said casket body and said upper marginal metallic molding, a casket cover seated on said cover supporting and sealing member, non-metallic slide cover supporting members 95 removably mounted within the upper marginal edges of said casket body, and slide covers in said slide cover supporting members beneath the horizontal plane of said casket cover supporting and sealing member. 100

3. In a metallic casket, a casket body made up of a single blank of sheet metal forming bottom and side walls, end walls welded therein, metallic moldings formed about the upper and lower marginal edges thereof, vertical corner and intermediate metallic moldings extending between said upper and lower marginal metallic moldings, casket slide cover supporting members within the upper marginal edges of said metallic casket 110 body and provided with non-metallic tacking strips adapted to support the casket lining material, slide covers within said slide cover supporting members, a casket cover adapted to rest upon said upper marginal metallic molding, and means for detachably connecting said cover in position.

4. In a metallic casket, a casket body made up of a single blank of sheet metal of substantially U-shape in cross section forming 125 bottom and side walls, end walls having welding flanges welded therein, hollow metallic moldings formed about the upper and lower marginal edges thereof, corner and intermediate hollow metallic moldings ex- 130

- tending between and welded to said upper and lower marginal metallic moldings, removable casket slide cover supporting members within said metallic casket body and
5 provided with non-metallic tacking strips adapted to support the casket lining material, slide covers within said slide cover supporting members above said tacking strips, a casket cover resting upon said upper marginal metallic molding, and means for 10 detachably connecting and sealing said cover.
- In testimony whereof I have affixed my signature.

CHRISTIAN V. LUCIUS.
